(57) **CLAIM**

The ornamental design for a mobile paint booth, as shown and described.

DESCRIPTION

FIG. 1 is a first perspective view of a mobile paint booth showing my new design;

FIG. 2 is a second perspective view thereof;

FIG. 3 is a front view thereof;

FIG. 4 is a back view thereof;

FIG. 5 is a top view thereof;

FIG. 6 is a bottom view thereof;

FIG. 7 is a left side view thereof;

FIG. 8 is a right side view thereof;

FIG. 9 is a perspective view thereof with the left and right-side end flaps shown in an open position; and the ventilation flaps shown in a lowered position;

FIG. 10 is a perspective view thereof with both the right and left-side and ventilation flaps shown in a lowered position;

FIG. 11 is an enlarged view of the selected portion 11 in FIG. 1; and,

FIG. 12 is an enlarged view of the selected portion 12 in FIG. 2.

The broken lines shown in the drawings depict portions of the mobile paint booth that form no part of the claimed design. The alternating length broken lines in FIGS. 1, 2, 11, and 12 depict the boundaries of the enlargements and also form no part of the claimed design.
